CLAIM

The ornamental design for a pharmaceutical tablet, as shown and described.

DESCRIPTION

FIG. 1 is a top perspective view of a pharmaceutical tablet showing our new design;

FIG. 2 is a top plan view thereof, the bottom plan view being a mirror image of that shown;

FIG. 3 is a front elevational view thereof, the rear elevational view being a mirror image of that shown; and

FIG. 4 is an end elevational view thereof, the opposite end elevational view being a mirror image of that shown.
